UNITED STATES PATENT OFFICE.

HUBERT A. MYERS, OF TOLEDO, OHIO.

DESIGN FOR A CANDY CONFECTION.

Application filed November 5, 1925. Serial No. 15,353. Term of patent 3½ years.

To all whom it may concern:

Be it known that I, HUBERT A. MYERS, a citizen of the United States, residing in Toledo, in the county of Lucas and State of Ohio, have invented a new, original, and ornamental Design for Candy Confections, of which the following is a specification, reference being had to the accompanying drawing, forming a part thereof, in which—

Fig. 1 is a perspective view, and
Fig. 2 an end elevation of a candy confection embodying my design.

I claim:

The ornamental design for a candy confection as shown.
